VALVE STEM GRINDING TOOL

Paul Murrah, Corinth, Miss.

Application February 17, 1939, Serial No. 257,004

11 Claims. (Cl. 51—98)

This invention relates to grinding tools and, although not necessarily limited thereto, to portable tools for grinding the ends of valve stems for internal combustion engines to a proper predetermined length.

The fuel intake and exhaust gas ports of internal combustion engines are usually controlled by valves operated in a predetermined sequence by means of tappets or push rods driven by the engine. For the most efficient operation of the engine, it is important that a proper clearance be provided between the tappet, or push rod, and the end of the valve stem. In certain types of engines, the adjustment of the valve is accomplished by grinding more or less metal from the end of the stem as determined by the distance between the valve seat in the cylinder block and the upper end of the valve tappet. This has usually necessitated the grinding of the valve stem by hit or miss methods until its proper length was obtained. Such methods are not only wasteful but time consuming and inaccurate.

It is an object of this invention to provide a new and improved portable tool for grinding the ends of valve stems for engines of the type referred to expediently and accurately.

It is a further object of this invention to provide a new and improved valve stem grinding tool which when once adjusted may be used for accurately finishing the ends of a plurality of valve stems of varying lengths without readjustment.

It is a still further object of this invention to provide a portable valve stem grinding tool which may be supported upon the engine cylinder block and which automatically and accurately determines the proper amount of grinding to be done on each of the engine valves.

In accordance with the illustrated embodiment, a portable valve stem grinding tool is provided which is adapted to be placed upon the cylinder block of the engine and seated upon the valve seat therein for the particular valve to be fitted, with means provided on the tool for holding the valve and other means for automatically positioning the grinding disk of the tool relative to the valve in accordance with the distance from the valve seat to the upper end of the valve push rod or tappet.

For a consideration of what I believe to be novel and my invention, attention is directed to the following description and the claims appended thereto taken in connection with the accompanying drawing.

In the drawing, Fig. 1 is a front elevation of the

tool embodying my invention and is shown fitted into a valve chamber of a cylinder block illustrated in cross-section; Fig. 2 is a side elevation of the tool; Fig. 3 is a cross sectional view of a detail taken along the line 3—3 and Fig. 4 is a cross-sectional view of a detail taken along the line 4—4.

The grinding tool comprises a circular base 10 having a cylindrical portion 11 depending therefrom which is adapted to fit snugly into the valve stem guide bearing passage 12 of an engine cylinder block 13. The base 10 is provided on its lower edge with a tapered face 14 which is adapted to seat firmly upon the valve seat of the cylinder block. Extending perpendicularly from the upper surface of the base 10 is a frame comprising a pair of substantially parallel side members 15 and 16 surmounted by an externally threaded cylindrical head 17. A valve holding template 18 is co-operatively threaded onto the head 17, the upper edge of which template is provided with an inwardly tapering seat 19 for co-operatively receiving a valve 20, the stem 21 of which is to be ground. For facilitating the insertion and removal of the valve into the tool and for manually rotating the valve during the grinding operation, diametrically opposite portions are removed from the upper end of the template so as to provide openings 22 exposing portions of the valve periphery substantially as indicated. The upper end of the head 17 has a semi-circular web 23 with a V-shaped notch 24 at the center thereof as shown in Fig. 3. Extending between the side frame members 15 and 16 is a transverse section, as at 25, having a V-shaped notch 26 therein. The notches 24 and 26, which are oppositely disposed with respect to each other, are adapted to receive the valve stem 21 and assist in maintaining the valve in the proper position in the tool during the grinding operation.

An electric motor 28, having a grinding disk 29 provided on the end of the shaft 30, is mounted for slideable movement vertically between the side frame members 15 and 16. As shown more clearly in Fig. 4, the motor end plate 31 is provided with an outwardly extending rectangular portion for co-operatively and slidably engaging with parallel facing surfaces 32 and 33 of the side members 15 and 16. The motor is retained upon the frame by means of the plate 34 which overlaps the members 15 and 16 and is secured to the motor end plate 31 as by a plurality of screws 35. The plate 34 is provided with side flanges 36 and 37 and a lower end flange 38 forming a guard 55

for the grinding disk. A gage rod 39 secured to the lower flange 38 of the plate 34 extends axially through the base 10 and the cylindrical portion 11, the end thereof being adapted to engage with the upper end of the valve tappet 40 of the engine and position the grinding disk relative to the valve to be ground as will be herein-after described.

The tool is adjusted by turning the adjustable template so that the distance from a predetermined point on seat 14 of the base 10 to a corresponding predetermined point on the seat 19 of the template is equal to the distance from the lower end of the gage rod 39 to the upper surface of the grinding disk 29. To correct for the necessary clearance to be allowed between the valve tappet and the lower end of the valve stem, the template is then moved the requisite few thousandths of an inch toward the grinding disk. For facilitating this latter adjustment, co-operating micrometric scales may be provided on the head 17 and the lower edge of the template 18, as indicated at 41 and 42. After the tool is adjusted, the template may be made fast 25 with respect to the head by tightening a suitably arranged set screw 43 contracting the lower rim of the template upon the head.

It is understood that, prior to the stem grinding operation, the valve face is first ground or otherwise fitted into the seat of the cylinder block in the conventional manner. The tool is then inserted into the valve chamber with the face 14 firmly resting on the valve seat of the cylinder block. The motor and grinding disk are then pushed downwardly until the end of the gage rod 39 contacts with the upper surface of the valve tappet 40. It is obvious that in this position the distance from the valve seat on the template 18 to the upper surface of the grinding disk 29 will be exactly equal to the distance from the valve seat of the cylinder block to the upper surface of the valve tappet 37 less the amount of correction made for clearance. The valve may then be inserted into the tool and with the motor driving the disk 26 the lower end of the valve stem 21 may be ground no more than the requisite amount. During the grinding operation the valve may be rotated by hand or by any other suitable means to insure the flat grinding of the stem end until the face of the valve rests squarely upon the seat 19 of the template. The tool is then shifted to the next valve seat for finishing the stem of the valve corresponding thereto.

As is well known by those skilled in the art, the distance between the various valve seats and the corresponding tappets in an engine cylinder block will vary appreciably, but, by the use of this tool, each valve stem is ground accurately to the proper length as is determined automatically by the mere insertion of the tool into each valve chamber. As the tool is moved from one valve chamber to the next and the grinding disk and motor moved downwardly until the gage rod 39 comes into contacting relationship with the corresponding valve tappet, each valve stem may in turn be finished with no separate measurements or other adjustments of the tool required during the course of an engine valve stem grinding job.

It is obvious that after a certain number of valve stems have been ground, the surface of the grinding disk 26 may become somewhat worn and correspondingly decreased in diameter. Therefore, it is desirable that the initial adjustment of the tool be checked periodically and that the

template 18 be readjusted to correct for any wearing of the grinding disk.

It is pointed out that this invention is not necessarily limited to valve grinding tools, but it is obvious that by simple modifications which may be made by one skilled in the art, it may be adapted for grinding other articles to a proper length as determined by the distance between two spaced apart points between which such article is to extend. Furthermore, while I have shown an electric motor for driving the grinding disk 26, it is obvious that any other suitable driving means may be substituted therefor, such as a manually operable crank mechanism. A remote source of power may also be coupled to the grinding disk by means of a suitable flexible shaft. It is further obvious that in lieu of the grinding disk 26, any other suitable cutting implement may be used for finishing the end of the valve stem.

While I have shown and described the principal of operation of my invention in what I consider to be the preferred embodiment thereof, I desire to have it understood that it is not limited to any precise construction or combination of elements as set forth, but includes within its scope whatever modifications come within the spirit of the appended claims.

What I claim as new and desire to secure by Letters Patent of the United States, is:

1. A valve stem grinding tool comprising a base having a face adapted to co-operatively rest on the valve seat of a cylinder block, a cylindrical portion depending from said base and adapted to snugly fit into the valve stem guide bearing passage in said cylinder block, a frame member extending upwardly from the upper surface of said base, a template secured to the upper end of said frame member for supporting a valve axially parallel with respect to the valve seat of said cylinder block, a grinding disk, means for slidably supporting said grinding disk on said frame member for movement in the axial direction with respect to the stem of said valve, a gaging rod operatively secured to said grinding disk supporting means and adapted to extend through said base and to engage with the valve tappet of the cylinder block and position said grinding disk with respect to said template.

2. A valve stem grinding tool comprising a base having a face adapted to co-operatively rest on the valve seat of a cylinder block, a cylindrical portion depending from said base and adapted to fit snugly into the valve stem guide bearing passage in said cylinder block, a frame member secured to the upper surface of said base, means for supporting a valve on said frame member, a grinding disk slidably arranged on said frame member and movable in the axial direction with respect to the stem of the valve and into engagement therewith, a gaging rod slidable with said grinding disk adapted to extend through said base and said cylindrical portion and engage with the corresponding valve tappet in the cylinder block for positioning said grinding disk relative to the valve supporting means.

3. A valve stem grinding tool comprising a base having means thereon for definitely positioning said tool with respect to the valve seat in a combustion engine cylinder block, a frame member extending from the upper surface of said base, a template provided on the upper end of said frame member having a seat for supporting a valve with the stem thereof depending downwardly therefrom, a grinding disk mounted

on said frame member and slidably thereon in the axial direction with respect to the valve stem and means for positioning said grinding disk relative to the valve seat of said template in accordance with the distance from the valve seat of the cylinder block to the valve tappet therein.

4. A valve stem grinding tool comprising a frame, a base on said frame adapted to co-operatively rest on the valve seat of an engine cylinder block, adjustable means for supporting a valve on said frame, a grinding disk slidably supported on said frame and movable in the axial direction with respect to the stem of the valve supported on said frame and into engagement there-

15 with, a gaging rod movable with said grinding disk adapted to extend into the cylinder block and engage with the corresponding valve tappet therein for positioning said grinding disk on said frame with respect to said valve supporting means.

20 5. A valve stem grinding tool comprising a frame having a base adapted to co-operatively rest on the valve seat of an engine cylinder block, a template on said frame for co-operatively receiving a valve, a grinding disk slidably arranged 25 on said frame member and movable in the axial direction with respect to the stem of said valve and into engagement therewith and means for automatically positioning said grinding disk with respect to said template in accordance with the 30 distance from the valve seat to the corresponding tappet in said cylinder block.

6. A valve stem grinding tool comprising a frame, means on said frame for positioning the head of the valve to be ground relative to the 35 valve seat of a cylinder block, a grinding disk movably mounted on said frame, and gaging means secured to the grinding disk mounting for automatically positioning said grinding disk on said frame into grinding relationship with the 40 end of the valve stem as determined by the distance between said valve seat and the corresponding valve tappet measured by said gaging means.

7. A valve stem grinding tool comprising a frame having a portion adapted to co-operatively 45 rest on a valve seat of a cylinder block, a rotatable grinding disk movably mounted on said frame, supporting means on said frame for a valve including means for guiding and limiting the movement of said valve toward said grinding disk, and gaging means secured to the grinding disk mounting for movement therewith for measuring the distance from said valve seat to the corresponding valve tappet and positioning said grinding disk accordingly relative to said valve 50 supporting means.

8. A valve stem grinding tool comprising a frame having a pair of spaced apart parallel members, means for holding a valve in said frame with the stem thereof extending parallel with said parallel members, a grinding disk slidably mounted on said parallel members, a measuring surface on said frame, and gaging means secured to said grinding disk mounting and slidable therewith for adjusting the position of said grinding disk relative to said valve holding means in accordance with the amount of grinding to be performed on the stem of said valve as measured by the distance between said gaging means and said measuring surface.

9. A tool for grinding an article to a predetermined length in accordance with the spacing between two relatively fixed points, said tool comprising a frame, a grinding disk movably mounted on said frame, means for supporting the article to be ground upon said tool including means 15 for guiding and limiting the movement of the article toward said grinding disk, means for holding said supporting means fixed with respect to one of said points and gaging means fixedly secured to the grinding disk mounting for movement therewith for measuring the distance from said one point to the second of said points and positioning said grinding disk accordingly relative to said article holding means.

10. A tool for grinding an article to a predetermined length as determined by the distance between two spaced apart points between which said article is to extend, said tool having means for positioning said article relative to one of said points, a grinding disk movably mounted on said tool, and gaging means fixedly secured to the grinding disk mounting for movement therewith for positioning said grinding disk relative to said article positioning means in accordance with the distance from said one point to the second point 30 as measured by said gaging means.

11. A grinding tool comprising a frame, a rotatable grinding disk slidably mounted on said frame, means on said frame for holding an article to be ground, a measuring surface on said 45 frame, gaging means secured to the grinding disk mounting and slidable therewith, said gaging means adapted to position said grinding disk relative to the article holding means in accordance with the measured distance between said 50 measuring surface and a point on said gaging means.
